UNITED STATES PATENT OFFICE.

ISAAC W. HENDERSON, OF OAK PARK, ILLINOIS.

NUMBER-DISPLAY DEVICE FOR AUTOMOBILES.

No. 907,497.

Specification of Letters Patent.

Patented Dec. 22, 1908.

Application filed January 30, 1908. Serial No. 413,404.

To all whom it may concern:

Be it known that I, ISAAC W. HENDERSON, a citizen of the United States, residing at Oak Park, county of Cook, and State of Illinois, have invented certain new and useful Improvements in Number-Display Devices for Automobiles, of which the following is a specification.

My invention relates to number display devices for automobiles, that is to devices for displaying the license number of the automobile.

The object of my invention is to provide a number display device which will exhibit the number as plainly at night as by daylight.

A further object of my invention is to provide a device as mentioned which shall present a neat or even ornamental appearance.

A further object of my invention is to provide a number display device as mentioned, in which the number may be readily changed to correspond with changes in the license number.

Other objects will appear hereinafter.

With these objects in view my invention consists generally in a lamp casing and lamp arranged therein, in combination with a plurality of annular, number bearing members rotatably mounted about said lamp, said casing having a longitudinal opening of sufficient size to display but one number at a time of each annular member, and said members and the numbers thereon being opaque and translucent respectively.

My invention further consists in a device as mentioned so constructed and arranged that the annular members may be readily turned to change the number displayed, and equipped with means for locking said members against accidental movement or displacement.

My invention further consists in various details of construction and arrangements of parts all as will be hereinafter fully described and particularly pointed out in the claims.

My invention will be more readily understood by reference to the accompanying drawings forming a part of this specification and in which,

Figure 1 is a side elevation of a number display device embodying my invention, Fig. 2 is a vertical cross section thereof, Fig. 3 is a central, vertical, longitudinal section

of the device, Fig. 4 is a perspective view of one of the annular number bearing members, Fig. 5 is a detail cross section upon an enlarged scale illustrating one form of locking device, Fig. 6 is a detail cross section illustrating a modified form of the locking device, and Fig. 7 is a detail longitudinal section through several of the annular members assembled.

In carrying out my invention the device may be arranged at any desired point upon the automobile, but I prefer to utilize the usual side lights for this purpose and have so illustrated it in the drawings.

Referring to the drawings, 1 indicates the lamp casing. This may be of any size or form desired but I prefer that it be cylindrical as shown. Secured to the front edge of the cylinder, 1 is an annular flange, 2, to which is fixed the front member, 3 carrying the glass or lens, 4.

5 indicates a lining for the lamp casing. This comprises a cylindrical member arranged concentrically within said casing and substantially co-extensive in length therewith. To the rear end of the lining, 5 is secured an annular flange or ring, 6 to which is secured in any suitable manner the back, 7 of the device, within which is arranged the reflector, 8.

It will be seen that the shell of the device is formed of two separate parts, one comprising the casing, 1 with the front secured thereto and the other the member, 5 with the back formed thereon. The members, 1 and 5 telescope as shown, the members, 2 and 6 forming stops to limit the movement of the members, 5 and 1 respectively.

9 indicates a plurality of tie-bolts extending through lugs, 2' and 6' on the members, 2 and 6 respectively for securing the device together.

10 indicates the lamp arranged within the shell.

It will be obvious that the portion of the device above described may be substantially of any desired form and that any style of lamp may be employed although I prefer the electric lamp as illustrated.

The casing, 1 and the cylinder, 5 are provided with corresponding longitudinally disposed openings, 11 and 12 respectively, extending substantially from end to end thereof and the former is closed by a glazed door, 110 13 hingedly connected as at 14 to the casing, 1.

Rotatably mounted between the members, 1 and 5 are a plurality of annular members, 15, there being sufficient difference in the sizes of the members, 1 and 5 to accommodate the annular members between them. Each member is formed of opaque material and is provided with a series of digits from 1 to 0 arranged consecutively thereon and formed of translucent material. 15^a indicates the digits. The members, 15 are arranged parallel, and together close or cover the longitudinal openings 11 and 12; and the openings are of sufficient size to display but one digit of each annular member at a time. 15 The desired number is obtained by rotating the several rings and there may be as many rings or members, 15 as desired, it being evident that the greater the number, the larger the range of the device. In the drawings I 20 have illustrated six, the range then being from 1 to 999,999. It is obvious that when less than six digits are required for the number to be displayed, several of the rings, 15 must appear blank. To this end each ring or 25 member, 15 is divided into eleven parts, ten of which are provided with translucent digits, and the other parts 15' being blank or opaque, and this latter part is turned in front of the openings, 11 and 12. 30 Various means may be employed to prevent the light from issuing from between the several rings, but I find that illustrated in the drawings both simple and efficient. This consists in shouldering or rabbeting the adjacent edges of the rings forming the overlapping peripheral flanges, 16. It is obvious that some means must be provided to prevent the jolting of the machine from displacing the rings, 15. This may be 40 done by tightening the bolts, 9, the combined width of the members, 15 in such case being slightly greater than the length of the members, 1 and 5 in order to clamp said members, that is, the rings, 15 between the flanges, 2 45 and 6. To facilitate turning the rings, the rings are provided with notches or indentations, 17 which may be readily engaged by the end of the finger when the door, 13 is opened. This also provides means for locking the rings against accidental displacement 50 instead of employing the bolts, 9 as before mentioned. To this end one of the cylinders, 1 or 5 is provided with a plurality of indentations, 18 arranged to enter one of the 55 indentations, 17 when the digits are in proper position with relation to the openings, 11, and 12, the several members being sufficiently resilient for this purpose. In Fig. 6 I have illustrated a modified form wherein 60 the notches or indentations, 17', 18' are formed oppositely from the notches or indentations, 17 and 18. It is obvious that it is not necessary to employ both casings, 1 and 5 particularly when 65 the outer casing is cylindrical; also that the

outer casing may be of any desired configuration when the inner cylinder is employed.

In using the device the number may be readily changed to conform to a change in license number and this is particularly advantageous with touring cars which pass from one jurisdiction to another. 70

Having described my invention what I claim as new and desire to secure by Letters Patent is:

1. A number display device for automobiles comprising a lamp casing and lamp arranged therein in combination with a plurality of number bearing annular members rotatably mounted within said casing and 80 having translucent portions, said casing having a longitudinal opening of sufficient size to display one digit of each annular member simultaneously, substantially as described. 85

2. A number display device for automobiles comprising a lamp casing having a longitudinal opening therein and a lamp arranged within said casing, in combination with a plurality of similar annular members 90 rotatably mounted within said casing and parallel with each other, each of said members having a plurality of translucent digits from 0 to 9 arranged at intervals thereon and said longitudinal opening being of sufficient size to display but one digit of each annular member simultaneously, substantially as described. 95

3. A number display device for automobiles comprising a lamp casing and lamp arranged therein, in combination with a plurality of number bearing annular members rotatably mounted within said casing and having translucent portions, said members being adapted for rotation independent of 10 each other and said casing having a longitudinal opening of sufficient size to display one digit of each annular member simultaneously, and a transparent closure for each opening, substantially as described.

4. A number display device for automobiles comprising a lamp casing having a longitudinal opening therein and a lamp arranged within said casing, in combination with a plurality of similar annular members 11 arranged parallel within said casing and rotatable independently of each other each of said members having a plurality of translucent digits arranged at intervals thereon, said longitudinal opening being of sufficient 12 size to display but one digit of each member at a time, said members also having a blank or opaque portion adapted to close said opening when desired as and for the purpose specified. 13

5. A number display device for automobiles comprising a lamp casing and lamp arranged therein, in combination with a plurality of similar annular members rotatably mounted within said casing and each having 1

a plurality of translucent digits arranged at intervals thereon, said casing having a longitudinal opening of sufficient size to display one digit of each annular member simultaneously and means to prevent light issuing from between said members as and for the purpose specified.

6. A number display device for automobiles comprising a lamp casing and lamp arranged therein, in combination with a plurality of number bearing annular members rotatably mounted within said casing, said casing having a longitudinal opening of sufficient size to display one digit of each annular member simultaneously and means for locking said members against accidental displacement as and for the purpose specified.

7. In a device of the class described, a lamp casing comprising a pair of concentrically arranged members each provided with a longitudinal opening registering with each other, in combination with a plurality of partially translucent number bearing annular members rotatably mounted between said concentric members and a lamp within said casing, substantially as described. 20 25

In testimony whereof I have signed my name to this specification in the presence of two subscribing witnesses.

ISAAC W. HENDERSON.
